United States Patent Office.

HENRY BERGER, OF NEW YORK, N. Y.

Design No. 2,661, dated June 4, 1867.

DESIGN FOR A CENTRE-PIECE.

The Schedule referred to in these Letters Patent and making part of the same.

TO ALL WHOM IT MAY CONCERN:

Be it known that I, HENRY BERGER, of New York, in the county and State of New York, have invented a new and useful improvement in Designs for Centre-Pieces; and I do hereby declare the following to be a full, clear, and exact description thereof, which will enable those skilled in the art to make and use the same, reference being had to the accompanying drawing forming part of this specification, which drawing represents in only one figure, my design, consisting of a central cluster of foliage surrounded by shell-work in different stages of completeness or development, the outer edge of the centre-piece being composed of foliage and drapery, the drapery consisting of narrow folds arranged to fill spaces left vacant by the foliage.

What I claim as new, and desire to secure by Letters Patent, is—

The design for an ornamental centre-piece, herein represented.

This specification signed this eighth day of April, 1867.

HENRY BERGER.
